BAND PASS AMPLIFIER COUPLING

Rene A. Braden, Merchantville, N. J., assignor to
 Radio Corporation of America, a corporation of
 Delaware

Original application December 12, 1929, Serial No.
 413,450. Divided and this application Septem-
 ber 16, 1932, Serial No. 633,441

6 Claims. (Cl. 178—44)

My present invention which is a division of application Serial No. 413,450, filed December 12, 1929 and issued as U. S. Patent No. 2,037,614, relates to amplifiers, and more particularly, to a band pass amplifier adapted to operate with a constant accepted band width.

In a co-pending application Serial No. 278,105 filed May 16, 1928, I have disclosed band pass amplifiers of the type comprising two or more circuits, each tuned to the mid-band frequency, and coupling means for the circuits arranged so as to produce a constant accepted band width. It was further shown, in the said application, that to produce this latter condition the coupling between the tuned circuits must vary as the circuits are tuned to various wave frequencies, the variation being such that the product of coupling and wave frequency is approximately constant. Coupling means of various types were, also, disclosed in the said application whereby the accepted band width was maintained at a constant value as the circuits were tuned to receive at various wave frequencies.

Now, I have discovered, by further experimentation, additional arrangements for coupling tuned circuits in a band pass amplifier of the type described in the above mentioned application. The method of coupling tuned circuits employs a single means, the latter being variable and linked to the tuning control in such a manner that, as the circuits are tuned for various wave frequencies, the coupling will be caused to vary in the proper way to maintain constant band width.

Accordingly, it is one of the main objects of the present invention to provide a method of, and means for, maintaining constant the band width passed in an amplifier which consists in variably coupling the primary and secondary tuned circuits of the amplifier, and linking the single coupling control to the tuning control so as to maintain said band with constant independently of the wave frequency to which the circuits are tuned.

Other objects of the invention are to improve generally the simplicity and efficiency of band pass amplifier coupling arrangements, and to provide devices of the latter type which are not only reliable in operation, but economical and simple to manufacture.

The novel features which I believe to be characteristic of my invention are set forth in particularity in the appended claims, the invention itself, however, as to both its organization and method of operation will best be understood by

reference to the following description taken in connection with the drawings in which I have indicated diagrammatically several circuit organizations whereby my invention may be carried into effect.

In the drawings,

Fig. 1 shows diagrammatically a novel type of coupling arrangement,

Figs. 2 to 9 inclusive show modified coupling arrangements embodying the present invention.

Referring, now, to the accompanying drawings in which like characters of reference indicate the same elements in the different modifications, the numeral 1 indicates an electron discharge tube of either the three electrode or four electrode type, and shown preferably as the latter, the incoming signal energy to be amplified being impressed between the grid and cathode of the tube and designated as "Input". The reference numerals 3 and 4 denote an inductance and condenser respectively thus forming the primary tuned circuit which is tuned to the mid-band frequency of the incoming signal.

The numerals 6 and 7 represent a condenser and inductance respectively, and form the secondary tuned circuit, which is also tuned to the mid-band frequency. The numeral 8 designates a second electron discharge device, preferably of the four electrode type, whose grid is connected to receive the voltage which is developed across the secondary circuit 6, 7. The term "Output", in each modification, represents the circuit to which any subsequent circuits are connected to employ the amplified output of the device 8.

It is to be understood that the circuits embodying my invention are intended to select a definite band of frequencies from any part of a relatively wide range of frequencies. For example, a broadcast receiver embodying the invention would be capable of selecting and amplifying all signal currents contained within a band 10 kilocycles in width and would be able to select this 10 kilocycle band from any part of the frequency spectrum between 550 kilocycles and 1500 kilocycles. The mid-band frequency in this case is equal to the carrier wave frequency, and the accepted band extends equally on each side of the carrier frequency.

Referring now to Fig. 1 in particular, the primary tuned circuit consists of the inductance 3 and the condensers 4 and 5 in series, and the secondary circuit consists of the coil 7 in series with the condensers 5 and 6. The circuits are tuned to the mid-band wave frequency by varying the inductances 3 and 7. The circuits

are coupled by the condenser 5, and variation of the coupling is effected by varying the capacity of 5. The variable inductances 3 and 7 and the condenser 5 are linked together mechanically in any suitable manner, as indicated by 12. The rate of variation of the coupling condenser 5 is so chosen that the band pass net-work transmits to the tube 8, thruout the frequency spectrum between 550 and 1500 kcs., a band of 10 kcs. wide. The particular mechanical coupling between the tuning elements and the coupling element is not important, and depends upon the nature of the circuit employed as well as upon the desires of those skilled in the art. 15 The essential object of this invention is to provide a means for mechanically and simultaneously adjusting the coupling reactance with the tuning reactances of the band pass network in such a way that the selected band is the same 20 width over the entire tuning range of the network. It will be noted that an inductance 2, in the plate circuit of the device 1, is coupled, as at M, to the inductance 3 and functions to transfer energy to the primary circuit, 3, 4 and 25 5 from the device 1.

In the modification shown in Fig. 2, it will be observed that the primary and secondary circuits are tuned by varying the condensers 4 and 6. The output terminals of the tube 1 are connected directly to the tuned circuit 3, 4, 5. Coupling condenser 5 is, again, arranged to be controlled simultaneously with the condensers 4 and 6 by a single tuning control 12.

The circuit shown in Fig. 3 is derived from that shown in Fig. 2, by interchanging the positions of inductance 3 and condenser 4; inductance 7 and condenser 6 being similarly interchanged. In addition, a capacity 3' is connected in series between the anode of device 1 and inductance 3, while the said anode is energized from a source B through an inductance 4'. In Figs. 1, 2 and 3, I have shown three alternative methods of coupling the anode circuit of a tube to the tuned circuit following. Usually any of 45 these methods can be used with any circuit if the tube is a screen grid tube, but with a three electrode tube the circuit of Fig. 1 is preferable.

Fig. 4 shows a circuit employing a novel type of variable coupling condenser, one form of which has been described in my copending application, Serial No. 278,105, filed May 16th, 1928. In this circuit the coil 3 and the variable condenser 4 constitute the primary circuit, the coil 7 and variable condenser 6 the secondary circuit, and the primary and secondary circuits are coupled by the electrostatic capacity between the plates 9 and 10 which are attached to the high potential ends of the condensers 4 and 6, respectively.

A metal plate 11 is connected to ground (i. e. to the filament side of the circuit) and is mounted so that it can be slid between the plates 9 and 10 or drawn out. It must be insulated from the plates 9 and 10, and should move in a plane parallel to them and half way between. The capacity between 9 and 10 is reduced by the plate 11, the amount of reduction being roughly proportional to the area of 11 which is between the plates 9 and 10.

By this means the coupling capacity can be reduced from a comparatively large value almost to zero, and the ratio of maximum to minimum capacity is much greater than can be secured with the conventional two-plate variable condenser of equal maximum capacity. Instead of 75 being mounted as indicated in the drawings, the

plate 11 may be mounted so as to rotate on the shaft which carries the rotor plates of the variable condensers 4 and 6, and the plates 9 and 10 could then be conveniently attached to and supported by the stator units of the condensers 5 and 6.

Fig. 5 shows a modification of the circuit of Fig. 4, in which the coupling capacity consists of the two condensers 9, 10 and 9', 10' in series. The capacities of these two condensers are controlled by the grounded plates 11 and 11'. This circuit is especially convenient when the condensers 4 and 6 are separated by a shield partition 22, because of the symmetrical arrangement with respect to the shield; and additionally, in view of the fact that the connections between condensers 4 and 6 and the coupling condensers do not pass through the shield.

Of course, the plates 11 and 11' are actuated with the rotors of condensers 4 and 6 in a manner similar to the actuation of plate 11 and the rotors of condensers 4, 6 as shown in Fig. 4.

In the modification shown in Fig. 6, the secondary tuned circuit consists of the coils 7 and 13 and the variable condenser 6 in series. The coil 13 is inductively coupled to the coil 3, the amount of mutual inductance M being controlled by changing the position of inductance 13 with respect to inductance 3. The coupling control is linked to the tuning control 12. 30

The modified coupling arrangement in Fig. 7 embodies the link circuit coupling devices described in my co-pending application Serial No. 390,468, filed September 5, 1929. The inductance 3, of the primary circuit, is tuned by the condenser 4 and coupled to the link circuit by the inductance 15. The latter is connected in series with a variable inductance 11, and a second coupling inductance 16, the latter being coupled to the inductance 7 of the secondary circuit. The coupling between the primary and secondary circuits is, thus, controlled by mechanically connecting the means for varying the inductance 11, with the rotors of tuning condensers 4 and 6. 40

The circuit shown in Fig. 8 is similar to the arrangement in Fig. 7, except for the fact that a variable coupling condenser 18 is employed instead of the variable inductance 11.

In Fig. 9 there is shown a capacity-coupled circuit, the primary circuit 4, 3 being coupled to the secondary 6, 7 by the variable condenser 19. The three variable condensers are varied simultaneously by the control 12. As explained in connection with Fig. 1, the rate of variation of the coupling reactances with tuning in each of Figs. 2 to 9 is such that the band width selected is constant over the entire tuning range. In each of the constructions shown in Figs. 2 to 9 the requirements of the particular case will determine the specific nature of the mechanical coupling between the coupling element and the tuning elements. 55

While I have indicated and described several systems for carrying my invention into effect, it will be apparent to one skilled in the art that my invention is by no means limited to the particular organizations shown and described, but that many modifications may be made without departing from the scope of my invention as set forth in the appended claims. 65

What I claim is:

1. A band pass amplifier comprising at least two tuned circuits, an electrostatic shield between said circuits, a variable coupling reactance 75

- positioned between one of said tuned circuits and the shield, a second variable reactance connected to the first reactance and disposed between the shield and the other tuned circuit, said reactances varying the coupling between the tuned circuits simultaneously with tuning adjustments so as to maintain the accepted band width constant.
2. A band pass amplifier comprising at least two tuned circuits, an electrostatic shield between said circuits, two coupling condensers connected in series between said circuits, one being placed on each side of the electrostatic shield, and a grounded adjustable member associated with each coupling condenser and arranged to be moved into or out of the space between the condenser plates, said coupling condensers varying the coupling between the tuned circuits simultaneously with tuning adjustments so as to maintain the accepted band width constant.
- 20 3. In combination, in a tunable band pass filter circuit, an oscillation circuit including an inductance coil and a variable tuning condenser, a second oscillation circuit including a coil and a second variable tuning condenser, a common means for simultaneously and similarly varying said condensers to tune both said oscillation circuits to a common desired modulated carrier frequency of the broadcast range, an untuned adjustable reactance common to both said oscillation circuits comprising the sole coupling means between them and providing sufficient coupling therebetween to impart a band pass characteristic to the filter circuit of a width equal to the modulation side bands of said carrier frequency, said reactance comprising at least one variable condenser connecting points of high alternating potential of said oscillation circuits, means for mechanically coupling a variable element of said adjustable reactance to said common means whereby said reactance is adjusted to vary said coupling as said oscillation circuits are tuned, the rate of variation of said reactance being chosen to maintain the said width of the said characteristic substantially constant throughout the tuning range of said variable condensers.
- 45 4. In combination, in a tunable band pass filter circuit, an oscillation circuit including an inductance coil and a variable tuning condenser, a second oscillation circuit including a coil and a second variable tuning condenser, a common means for simultaneously and similarly varying said condensers to tune both said oscillation circuits to a common desired modulated carrier frequency of the broadcast range, an untuned adjustable reactance common to both said oscillations varying the coupling between the tuned circuits simultaneously with tuning adjustments so as to maintain the accepted band width constant.

tion circuits comprising the sole coupling means between them and providing sufficient coupling therebetween to impart a band pass characteristic to the filter circuit of a width equal to the modulation side bands of said carrier frequency, said reactance comprising at least one condenser having a pair of stator plates connected to similar high frequency potential points of said oscillation circuits and an adjustable plate connected to a point of lesser high frequency potential value, means for mechanically coupling said adjustable plate to said common means whereby said reactance is adjusted to vary said coupling as said oscillation circuits are tuned, the rate of variation of said reactance being chosen to maintain the said width of the said characteristic substantially constant throughout the tuning range of said variable condensers.

5 5. The combination of two alternating current circuits and a pair of spaced planar metallic plates connected to high alternating voltage points of said circuits, and at least one metallic plate at a relatively lower alternating voltage disposed in a plane intermediate the planes of said pair of plates, said three plates providing coupling between the circuits and said intermediate plate being adjustable with respect to the other two plates to vary the magnitude of said coupling.

20 6. In combination, in a tunable band pass filter circuit, an oscillation circuit including an inductance coil and a variable tuning condenser, a second oscillation circuit including a coil and a second variable tuning condenser, a common means for simultaneously and similarly varying said condensers to tune both said oscillation circuits to a common desired modulated carrier frequency of the broadcast range, coupling means connected to both said oscillation circuits comprising the sole coupling means between them and providing sufficient coupling therebetween to impart a band pass characteristic to the filter circuit of a width equal to the modulation side bands of said carrier frequency, said coupling means comprising at least one condenser having a pair of stator plates and an adjustable plate disposed intermediate the stator plates, means for mechanically coupling said adjustable plate to said common means whereby said coupling means is adjusted to vary said coupling as said oscillation circuits are tuned, the rate of variation of said coupling means being chosen to maintain the said width of the said characteristic substantially constant throughout the tuning range of said variable condensers.

RENE A. BRADEN.
